UNITED STATES PATENT OFFICE.

JOHN D. GRABILL, OF WOODSTOCK, VIRGINIA.

GRADING MACHINE.

Application filed October 7, 1927. Serial No. 224,664.

This invention relates to improvements in grading machines and more particularly has to do with machines for grading fruits and vegetables, especially apples and the like, and of the type in which is employed an endless traveling sizing chain or a series of such chains.

The object of the invention is to provide an improved machine of the general kind referred to that will operate in an efficient way to effect a thorough, rapid, satisfactory separation of the fruit, vegetables, or the like into different sizes or grades without injury thereto.

15 An important novel characteristic of the invention resides in the special chain supporting roll structure provided in combination with the particular construction of sizing chain whereby crushing of the fruit, vegetables, or the like between portions of the sizing chain and supporting roll is prevented.

Another important feature of the invention lies in the special sizing chain structure and the particular construction of supporting roll 25 in combination with a transfer apron, the particular construction of sizing chain and supporting roll providing for the arrangement of the transverse apron sufficiently close to the outer face of the supporting roll so that 30 wedging, clogging and crushing of the fruit, vegetables, and the like, between the supporting roll and the adjacent end of the transfer apron, is avoided, and the passage of the fruit, vegetables, or the like through the machine 35 from one sizing chain to another is facilitated to a material extent.

The invention comprehends a chain supporting roll provided with channels in the outer face thereof corresponding in size and 40 arrangement to and adapted to receive within the same the sizing chain structure as it passes over the roll.

A further object of the invention is to provide an improved chain supporting roll of the 45 character referred to and which will be of simple, light, strong, durable, inexpensive construction, which will provide for the free escape of water and dirt from its channels and that will maintain its shape and chan- 50 neled formation for proper cooperation with the sizing chain.

The invention, with other objects, novel features, and advantages thereof will be understood from the hereinafter contained de- 55 tail description, when considered in connection with the accompanying drawings form-

ing part hereof and illustrating one embodiment of the invention.

In the drawings:

Figure 1 is a top plan view of a grading 60 machine construction in accordance with the present invention.

Figure 2 is a central longitudinal vertical section.

Figure 3 is a detail section on an enlarged 65 scale, of the roll at the delivery end of one of the sizing chains, the adjacent forward roll of another sizing chain and the transfer apron.

Figure 4 is a detail view, on an enlarged 70 scale, of a portion of one of the sizing chains.

Figure 5 is a detail view, on an enlarged scale, of a portion of the sizing chain structure with parts shown in section.

Figure 6 is a section on the line 6—6 of Fig. 75 ure 5 looking in the direction of the arrow.

Figure 7 is a section on the line 7—7 of Figure 5.

Figure 8 is a detail view, on an enlarged 80 scale, of one of the supporting rolls for the sizing chain.

Figure 9 is a detail longitudinal section of the supporting roll structure illustrated in Figure 8.

Figure 10 is a transverse section, on an en- 85 larged scale of the supporting roll illustrated in Figure 8.

Figure 11 is an end elevation, on an en- 90 larged scale, of the supporting roll.

Figure 12 is a detail side elevation, on an enlarged scale, of one of the end sprocket 95 wheel members of the roll.

Figures 13 and 14 are detail views of one of the detachable extension sections of the side boards.

While a specific embodiment of the invention is illustrated in the drawings, it will of course be understood that changes and variations may be made in the particular construction shown, and the invention carried out in 100 other forms, as will appeal to those skilled in the art and falling within the scope of the appended claims without departing from the spirit of the invention.

Referring to a detail description of the 105 particular embodiment of the invention illustrated in the drawings, A designates the main frame of the machine. This may be of any suitable construction, the same being shown, in this instance, as comprising uprights 1 and upper and lower side rails 2, 3. Mounted on the upper part of the frame A is a plurality

of endless traveling sizing chains having different sized grading openings, said sizing chains being arranged end to end in series progressively in accordance with the size of 5 the grading openings therein and with the chain having the smaller size openings in advance. In this instance, two of such sizing chains are shown, designated B—C.

The structure of the sizing chains B—C is 10 the same as that shown in my Patent No. 1,636,227 dated July 19, 1927. The chain structure comprises rigid transverse rod members 4 and series of intermediate longitudinal link members 5 pivotally connected therewith and spaced to provide grading 15 openings 6 of similar size. The transverse rod members 4 consist of stout metal rods circular in cross section and having smooth outer faces. The longitudinal link members 20 5, which are shown circular in cross section, may be formed from heavy wire, said members being provided with eyes 6^a at either end to engage the transverse rod members 4. On the transverse rod members 4 between the 25 longitudinal link members 5 are tubular members or sleeves 7, said members or sleeves while serving as spacing means for the longitudinal link members 5 being rotatable on the transverse rod members 4. At either side of 30 the chain is a set of outer longitudinal link members 8 similar in construction to the link members 5 and pivotally connected to the transverse rod members 4 at the outer end portions thereof, said outer sets of link members 35 8 with the outermost of the series of links 5, and the outer end portions of the transverse rod members 4 constituting outer marginal sections, designated D, to cooperate with sprocket wheels. 9 designates spacing 40 sleeves on the transverse rod members 4 between the longitudinal links 8 and the outermost of the series of link members 5. The transverse rod members 4 are provided at their ends with suitable retaining means, the 45 same being here shown in the form of integral heads on the rod members 4, and one of the transverse rod members being shown provided with a cotter pin 10.

The supporting and driving means for the 50 sizing chains B—C, comprises pairs of rolls 11—12 and sprocket wheels 13—14 located at either end of said rolls to cooperate with the side marginal sections D of the sizing chains B—C, said rolls and sprocket wheels being 55 fixedly secured to shafts 15—16—17, 18 respectively which are mounted in suitable bearings on the frame A.

The arrangement of the pairs of supporting rolls 11—12 is preferably, as shown, so 60 that the upper stretch of the sizing chains B—C are supported at an inclination, the shafts 16—18 of the rolls 12 being shown arranged above the horizontal plane of the shafts 15—17 of the rolls 11, and the rolls 65 12 being of greater diameter than the rolls 11.

The forward rolls 11 of the sizing chains B—C, are shown with smooth outer faces, and the sprockets 13 at the ends of said rolls project radially outward beyond the outer face of the same to engage the outer side sections 70 D of the sizing chains, the main part of the sizing chains that have the sizing openings 6 engaging over the smooth face of the roll.

In accordance with my present improvements, the roll 12 at the delivery end of each 75 of the sizing chains B—C, is provided in its outer face with circumferential channels 19 and longitudinal channels 20 corresponding in size and arrangement to the open sizing chain structure to receive the same therein when passing around said rolls. Also the 80 diameter of the end sprocket wheel members 14 of the rolls 12 is substantially equal to that of said rolls, and the depth of the sprockets 21 of said end sprocket wheel members which 85 are engaged by the outer end portions of the transverse rod members 4, is sufficient so that the sizing chain structure in passing over the rolls 12, is received within the circumferential and longitudinal channels 19—20, with 90 its outer face within the confines of or substantially flush with the outer face of the said rolls. As the sizing chain passes around the roll 12, the open sizing chain structure is received within the circumferential and longitudinal channels 19—20 of the roll and 95 the portions 22 of the periphery of the rolls 12 bounded by the said channels 19—20, which substantially correspond in shape and size to the grading openings 6 of the sizing 100 chain, as will be understood, enter the grading openings 6 of the chain, so that any of the fruit or vegetables that may be extending partially through openings of the sizing chain are forced by the portions 22 of the roll 12 upwardly out of the grading openings 6 105 to and supported at the upper side of the sizing chain whereby crushing of the fruit or vegetables between portions of the sizing chain and the roll at the delivery end of the sizing chain is prevented. The rotatable sleeves 7 on the transverse rods 4 of the sizing chain prevent wedging of the fruit, vegetables or the like in the openings of the chain, 110 and also insure smoothness of operation in the movements of the portions 22 of the rolls 115 12 into and out of the sizing openings 6 of the chain between the transverse rod members 4 thereof.

The construction of the rolls 12 illustrated 120 in the drawings comprises a central shaft member 23, and end sprocket wheel members 14 fixed to said shaft by screws 24 or other suitable means. The periphery of the rolls 12 is made up of longitudinal bars or slats 25 arranged circumferentially in parallel spaced 125 relation and bridging the space between the end sprocket members 14. The bars or slats 25 are supported and held fixed with relation to the end sprocket wheel members 14 by series of cross shaped ribs 26 on the inner 130

sides of the end sprocket wheel members 14 interfitting with correspondingly shaped grooves 27 in the end of the longitudinal bars or slats 25. 28 designates supports on the 5 central shaft 23 for the longitudinal bars or slats 25 intermediate their ends. Said supports are in the form of circular pieces having a central opening 28^a to engage the shaft 23 and are arranged, as shown, inwardly of 10 the end sprocket wheel members 14. In the particular construction shown, the supports 28 are held in position against longitudinal movement on the shaft 23 by brads 29 passing through the longitudinal bars or slats 15 25 into the peripheral portion of said supports but any other means suitable for the purpose may be employed. 30—30 designates 20 respectively bolts and nuts for tying the end sprocket wheel members 14 together in tight interfitting relationship with the bars or slats 25, said bolts, as shown, extending longitudinally through suitable openings in the end sprocket wheel members 14 and the supports 28. In this particular embodiment of 25 the invention, as will be understood, the longitudinal channels 20 of the rolls 12, which are adapted to accommodate the transverse rod members 4 of the sizing chain, are provided by the spaces between the longitudinal 30 bars or slats 25, the circumferential grooves 19 of the rolls 12, which receive the longitudinal series of link members 5 of the sizing chain, are provided by transverse grooves 25^a in said longitudinal bars or slats. The 35 longitudinal bars or slats 25 have rounded outer face portions 32, as shown.

In the composite construction of the rolls 12 hereinbefore described, the longitudinal bars or slats 25 and the supports 28 are constructed of wood, the end sprocket wheel members 14 being formed of metal. The resulting structure is simple, light weight, and inexpensive, at the same time it is of a strong, serviceable nature, will retain its shape and 40 channel formation to properly register with the transverse rod members 4 and longitudinal link members 5 of the sizing chain, and the open formation provides for the ready escape of moisture and dirt from its chain 45 receiving channels.

Any suitable power means may be employed for operating the sizing chains B—C. In the drawings a motor 33 is shown for this purpose. The motor 33, which is mounted on the lower part of the frame A, is connected by a belt 34 with a pulley 35 on the shaft 17 from which motion is transmitted to shaft 15 through the medium of a sprocket chain 36 engaging pinions 37—38 on shafts 15—16. 50 The sizing chains B—C may be operated manually by a hand crank 39 adapted to be applied to one of the shafts 15—18, the same being shown engaged with the shaft 18.

The machine is provided with a hopper 40 55 at its forward end and with a suitable receiv-

ing table 41 at its discharge end. 42 are side boards extending alongside the sizing chains B—C for holding the fruit, vegetables or the like thereon. The side boards 42 are divided, as shown, to provide vertical openings or slots 43 at the points of location of the shafts 16—18 of the rolls 12, in order to provide for the ready assembly and removal of said rolls, and said side boards are provided with removable sections 44 adapted to 70 fit upon the upper edge faces thereof and bridge the said openings. The removable sections 44 which are shown arcuate shape, are provided with U-shaped clips 45 to embrace the side boards 42. The bases of said clips 75 are set in the bottom faces 46 of said removable sections so that the latter can fit close against the upper edge faces of the side boards 42, said removable sections being provided with recesses 47 in their bottom faces 80 to receive the bases of said clips, which latter are secured to the removable sections 44 by screws 48 or equivalent means. The removable sections 44 with the openings or slots 23 in the side boards 42 not only provide for 85 the ready removal of the rolls 12 but said sections extend along the ends of the said rolls, furnishing the necessary increased height of retaining board at this point, permitting the side boards 42 to be of uniform and less 90 height throughout the machine.

Between the pairs of supporting rolls 11, 12, at either side of the machine on the side rails 2 of the frame A are provided longitudinally extending slide ways for the outer 100 side marginal sprocket engaging portions D of the active stretch of the sizing chains B—C, said slide ways comprising spaced rail members a, b the bottom rail member b of said ways constituting tracks upon which the 105 outer side portions D of the sizing chain slide and are supported.

49 designates transversely extending slatted aprons positioned below the upper stretch of the sizing chains B—C to receive 110 and convey the fruit, vegetables or the like that may drop through the openings of the sizing chains to one side of the machine.

Aprons 50 are employed for transferring the fruit, vegetables or the like from the sizing chain B to the succeeding sizing chain C and from the latter to a receiving table 41 at the discharge end of the machine. In accordance with the present invention, the forward end of the aprons 50 are arranged close 115 to the outer face of the rolls 12. This, as will be appreciated, is made possible by the special construction of the rolls 12 channeled to receive within the same the sizing chains B—C. It is only necessary to allow sufficient 120 clearance for the operation of the rolls 12, and the aprons 50 can therefore be set close to the face thereof. This is of considerable importance since with the longitudinal links 5 and transverse rod members 125 130

- 4 of the sizing chains entered within the channels 19—20 of the rolls 12, and the aprons 50 disposed close to the face of the roll, smaller size fruit, vegetables or the like will not be 5 caught and crushed between the transverse rod members 4 of the sizing chain and the forward end of the apron. In the particular exemplification of the invention illustrated in the drawings, the aprons 50 are pivotally 10 supported at their upper forward ends on side boards 42 by rods 53, said rods engaging tubular portions 50^a of the aprons 50 and bearings 54 on the side boards 42.

As will be understood in the operation of 15 the machine the apples or the like, are fed to the hopper 40 onto the first endless traveling chain B. The smaller sized apples drop through the grading openings in the upper stretch of the sizing chain B, the intermediate 20 size apples being carried to and dropping through the openings of the succeeding chain C, and the large sized apples being carried by the chains B—C to the receiving table 41; the smaller and intermediate grades of apples 25 that drop through the grading openings of the sizing chains B—C being delivered by the aprons 49 to one side of the machine.

What I claim is:

1. In a grading machine, an endless traveling sizing chain provided with sizing openings and having at either side thereof an outer marginal section to engage a sprocket wheel, and supporting and driving means for the sizing chain comprising a supporting 30 roll provided in its outer face with channels arranged to accommodate within the same the open sizing chain structure as it passes over said roll, and sprocket wheels at the ends of the roll engaging the outer marginal sections 35 of the sizing chain.

2. In a grading machine, an endless traveling sizing chain provided with sizing openings and having at either side thereof an outer marginal section to engage a sprocket wheel, and supporting and driving means for the sizing chain comprising a supporting roll at the delivery end of said sizing chain provided in its outer face with channels arranged to accommodate within the same the open sizing chain structure as it passes over 45 said roll, and sprocket wheels at the ends of the roll engaging the outer marginal sections of the sizing chain.

3. In a grading machine, an endless traveling sizing chain provided with sizing openings and having at either side thereof an outer marginal section to engage a sprocket wheel, and supporting and driving means for the sizing chain comprising a roll at the delivery 50 end of said sizing chain provided in its outer face with channels arranged to accommodate within the same the open sizing chain structure as it passes over said roll, and sprocket wheels at the ends of the roll engaging the outer marginal sections 55 of the sizing chain,

in combination with a transfer apron at the delivery end of the sizing chain having one end thereof disposed close to the outer face of said roll.

4. In a grading machine, an endless traveling sizing chain provided with sizing openings, and supporting and driving means for the sizing chain comprising a roll at the delivery end of the sizing chain provided in its outer face with channels arranged to accommodate within the same the open sizing chain structure in its passage over said roll, a second endless traveling sizing chain, supporting and driving means for the last mentioned sizing chain, in combination with a 80 chute arranged to transfer material from the first mentioned sizing chain to the second sizing chain, said chute extending transversely with one end thereof close to the outer face of the roll at the delivery end of 85 the first mentioned sizing chain.

5. In a grading machine, an endless traveling sizing chain comprising transverse rod members, series of longitudinal link members pivotally connected therewith and spaced to provide grading openings, and supporting and driving means for the chain comprising a roll having circumferential and longitudinal channels in its outer face to receive within the same the transverse rod members 90 and longitudinal link members in the passage of the chain over said roll.

6. In a sizing machine, an endless traveling sizing chain comprising transverse rod members and series of intermediate longitudinal link members pivotally connected therewith and spaced to provide grading openings, and supporting and driving means for the chain comprising a roll at the delivery end of the chain having circumferential and longitudinal channels in its outer face to receive within the same the transverse rod members 100 and longitudinal link members in the passage of the chain over said roll.

7. In a sizing machine, an endless traveling sizing chain comprising transverse rod members and series of intermediate longitudinal link members pivotally connected therewith and spaced to provide grading openings, and supporting and driving means for the chain comprising a roll at the delivery end of the chain having circumferential and longitudinal channels in its outer face to receive within the same the transverse rod members 110 and series of longitudinal link members in the passage of the chain over said roll in combination with a transfer apron at the delivery end of the chain arranged with one end thereof extending close to the outer face of said roll.

8. In a grading machine, an endless traveling sizing chain comprising transverse rod members, series of intermediate longitudinal link members pivotally connected therewith and spaced to provide grading openings, and 120

said chain having at either side thereof an outer marginal section to engage a sprocket wheel, and supporting and driving means for the chain comprising a roll having circumferential and longitudinal channels in its outer face to receive within the same the transverse rod members and longitudinal link members in the passage of the chain over said roll, and sprocket wheels at the ends of 10 the roll engaging the outer marginal sections of the chain.

9. In a sizing machine, an endless traveling sizing chain, said chain comprising transverse rod members, series of intermediate longitudinal link members pivotally connected therewith and spaced to provide grading openings, and a set of outer longitudinal link members pivotally connected with outer end portions of the transverse rod members at 20 either end thereof, said outer longitudinal link members being spaced from the outermost of the first mentioned series of longitudinal link members to cooperate therewith and with the end portions of said transverse 25 rod members to constitute side sprocket chain portions, and supporting and driving means for the sizing chain comprising a roll at the delivery end of the chain provided with circumferential and longitudinal channels to 30 receive within the same the first mentioned series of longitudinal link members and the transverse rod members in the passage of the chain over said roll, and sprocket wheels at the ends of said roll engaging the side 35 sprocket chain portions of the sizing chain.

10. In a sizing machine, an endless traveling sizing chain comprising transverse rod members and series of intermediate longitudinal link members pivotally connected therewith and spaced to provide grading 40 openings, and sleeve members rotatably mounted on the transverse rod members between the longitudinal link members, and supporting and driving means for the chain comprising a roll at the delivery end of the 45 sizing chain having circumferential and longitudinal channels in its outer face to receive within the same the transverse rod members and series of longitudinal link members in 50 the passage of the chain over said roll.

11. In a grading machine, an endless traveling sizing chain, and a supporting roll for the chain comprising end members, longitudinal bars interposed between the end members and forming the periphery of the roll, said end members and the said longitudinal bars at the ends thereof having portions interfitting to hold the bars against movement 55 relatively to the end members, means extending longitudinally of the roll inwardly of said bars for securing the end members and bars together, said bars being spaced and provided with transverse grooves in their outer faces, the spaces between the bars and the said grooves being adapted to receive 60 within the same the sizing chain structure when the same passes over the roll, and supporting means for the bars on said shaft intermediate the end members.

within the same the sizing chain structure when the same passes over the roll.

12. In a grading machine, an endless traveling sizing chain, and supporting and driving means therefor including a shaft, a roll 70 on said shaft comprising sprocket wheels fixed on the shaft and constituting end members, bars interposed in spaced relation between the sprocket wheels and forming the periphery of the roll, said sprocket wheels 75 and said bars at their ends having portions interfitting to hold the bars against movement relatively to the sprocket wheels, and rods extending longitudinally of the roll inwardly of said bars for securing the sprocket 80 wheels and bars in tight interfitting relation.

13. In a grading machine, an endless traveling sizing chain, and a supporting roll for the chain comprising end members, longitudinal bars interposed between the end members and forming the periphery of the roll, said end members and the said longitudinal bars at the ends thereof having portions interfitting to hold the bars against movement 85 relatively to the end members, means extending longitudinally of the roll inwardly of said bars for securing the end members and bars together, said bars being spaced and provided with transverse grooves in their outer faces, the spaces between the bars and the said grooves being adapted to receive 90 within the same the sizing chain structure when the same passes over the roll, and supporting means for the bars on said shaft intermediate the end members. 95

14. In a grading machine, an endless traveling sizing chain, and supporting and driving means therefor including a shaft, a roll on said shaft comprising sprocket wheels fixed 100 on the shaft and constituting end members, bars interposed in spaced relation between the sprocket wheels and forming the periphery of the roll, said sprocket wheels and said bars at their ends having portions interfitting to hold the bars against movement relatively to the sprocket wheels, rods extending 105 longitudinally of the roll inwardly of said bars for securing the sprocket wheels and bars in tight interfitting relation, and circular supporting pieces on the shaft intermediate 110 the sprocket wheels for supporting said bars. 115

15. In a grading machine, an endless traveling sizing chain, and supporting and driving means therefor including a shaft, a roll on said shaft comprising sprocket wheels fixed 120 on the shaft and constituting end members, bars interposed in spaced relation between the said sprocket wheels and forming the periphery of the roll, said sprocket wheels having angularly related rib portions projecting from the sides thereof, and the ends of said bars being provided with angularly related grooves to interfit with the said rib portions of the sprocket wheels, and rods extending 125 longitudinally of the roll inwardly 130

of said bars for securing the sprocket wheels and bars together.

16. In a grading machine, an endless traveling sizing chain including transverse rod members and series of intermediate longitudinal link members pivotally connected therewith and spaced to provide grading openings, and supporting means for the chain including a roll comprising end members, longitudinal bars secured to the end members and forming the peripheral part of the roll, said bars being spaced from each other and provided in their outer faces with transverse grooves, the spaces between the said transverse bars and said transverse grooves therein being adapted to receive within the same the transverse rod members and longitudinal link members of the chain when the same passes over the roll.

17. In a grading machine, an endless traveling sizing chain including transverse rod members and series of intermediate longitudinal link members pivotally connected therewith and spaced to provide grading openings, and supporting means for the chain including a roll comprising end members, longitudinal bars of general rectangular shape in cross section secured to the end members and forming the peripheral part of the roll, said bars being spaced from each other and provided in their outer faces with transverse grooves, the spaces between the said transverse bars and the said transverse grooves therein being adapted to receive within the same the transverse rod members and longitudinal link members of the chain when the same passes over the roll.

18. In a grading machine, a main frame, a grading chain, supporting and driving means

for the chain including a shaft mounted on the main frame, means on the shaft for engaging the chain, bearings for said shaft located on the upper side of the frame, side boards on the frame, said side boards being divided to provide openings at either side of the frame to provide for the removal of the said shaft, and side board extension sections adapted to fit upon the upper side edge faces of the side boards and bridge said openings, said extension sections being provided with substantially U-shaped clips to embrace the side boards and hold the same in place thereon.

19. In a grading machine, an endless traveling grading chain having sizing openings, and a supporting roll for the chain comprising end members and longitudinal bars extending between and secured to the end members, said bars being spaced from each other and provided with grooves in their outer faces, the spaces between the bars and the said grooves being adapted to receive within the same the sizing chain structure when the same passes over the roll.

20. In a grading machine, an endless traveling sizing chain provided with sizing openings, and supporting and driving means for the sizing chain comprising a supporting roll at the delivery end of the sizing chain provided in its outer face with channels arranged to accommodate within the same the open sizing chain structure as it passes over said roll, in combination with a transfer apron at the delivery end of the sizing chain having one end thereof disposed close to the outer face of said roll.

In testimony whereof I hereunto affix my signature.

JOHN D. GRABILL.
